UNITED STATES PATENT OFFICE.

STEPHEN O. DE ORLOW, OF AKRON, OHIO.

FAN.

1,205,600.

Specification of Letters Patent.

Patented Nov. 21, 1916.

Application filed April 16, 1915. Serial No. 21,741.

To all whom it may concern:

Be it known that I, STEPHEN O. DE ORLOW, a citizen of the United States, residing at Akron, in the county of Summit and 5 State of Ohio, have invented a new and useful Fan, of which the following is a specification.

The device forming the subject matter of this application is a hand fan adapted to be 10 employed by bootblacks and others for creating a forced draft.

One object of the invention is to provide novel means for imparting a movement to the member which carries the fan blades.

15 Another object of the invention is to provide novel means whereby at the will of an operator, the fan blades may be held in an operative, laterally projecting position, or in a folded position.

20 It is within the province of the disclosure to improve generally and to enhance the utility of devices of that type to which the present invention appertains.

With the above and other objects in view 25 which will appear as the description proceeds, the invention resides in the combination and arrangement of parts and in the details of construction hereinafter described and claimed, it being understood that changes in 30 the precise embodiment of the invention herein disclosed can be made within the scope of what is claimed, without departing from the spirit of the invention.

In the accompanying drawing: Figure 1 35 shows the invention in longitudinal section, parts appearing in elevation; Fig. 2 is a cross section on the line 2—2 of Fig. 1; Fig. 3 is an end elevation, wherein sundry parts have been sectioned, the line 1—1 on Fig. 3 40 indicating the cutting plane on which Fig. 1 is taken; Fig. 4 is a cross section on the line 4—4 of Fig. 1.

In carrying out the present invention there is provided a support denoted generally by the numeral 1. The support 1 may be of various constructions, but in the present instance it is a composite structure, comprising a thimble 2 having laterally projecting finger pieces 3, a tube 4 threaded or 50 otherwise fixed in one end of the thimble 2, and a guide tube 5 secured to the other end of the thimble.

The invention includes a slide 6 in the

form of a tube mounted to reciprocate on the guide tube 5, the slide 6 being provided at 55 one end with a head 7. In operation, the fingers of the operator are engaged with the elements 3, the palm of the hand of the operator engaging the head 7 to advance the slide 6 on the guide tube 5, for a purpose 60 which will be more clearly understood when the description is proceeded with.

Mounted within the guide tube 5 and secured thereto is an abutment ring 8. Disposed within the guide tube 5 and the slide 6 is a compression spring 9, one end of which engages the abutment ring 8, the other end of which engages the head 7. The spring 9 preferably is of helical form, and within the spring is located a shaft 10, one 70 end 11 of which is held for rotation in the head 7 but is so mounted therein that the head and the slide tube 6 cannot move longitudinally independently of the shaft. The shaft 10 is provided with threads 12, it being understood that the shaft is not threaded into the abutment ring 8, but slides freely 75 therein.

The invention comprises a tubular primary clutch 14 with which the threaded portion 12 of the shaft 10 is engaged, the primary clutch at times being engaged with the abutment ring 8. Projecting from the shaft 10 and located between the threaded ribs 80 thereof is a projection in the form of a pin 16 which coacts with the clutch 14 in a manner to be described hereinafter.

Secured in the outer end of the tube 4 is an abutment ring 17 and journaled in the abutment ring 17 is a secondary tubular 90 clutch 18 provided at one end with teeth 19 adapted to coöperate with the teeth 15 of the primary clutch 14. The secondary clutch 18 is equipped with an annular, inner shoulder 20 coacting with the abutment ring 17 to prevent outward movement of the clutch, the clutch being provided with an outer shoulder 30 and terminating in a tubular, externally threaded stem 22.

Surrounding the stem 22 of the secondary 100 clutch 14 is a carrying member 23 in the form of a ring, the same abutting against the shoulder 30 on the clutch 18. The carrying ring 23 may be provided as shown in Fig. 2 with radial ears 24 disposed in pairs, 105 brackets 25 being pivoted between the ears

24 of each pair, the brackets being secured respectively to blades 26. Any other suitable means may be provided for pivotally connecting the blades 26 with the carrying 5 member or ring 23 and since the blades may be of any desired form, a detailed description thereof is not necessary, beyond the statement that they may be made of celluloid or some other substance which, although sufficiently rigid to create a draft, 10 will not be so inflexible as to inflict injury, should they come in contact with garments of a person, or with an object of any sort. The blades 26, it is to be noted, are pivotally assembled with the carrying member 15 23 intermediate their ends, the inner ends of the blades being bifurcated to form fingers 27 lying on opposite sides of the stem 22 of the clutch 18. Threaded onto the stem 20 22 is a nut 28 which may be described as a tubular member adapted to engage the fingers 27 of the blades 26, to bind the same together and to hold the fingers of one blade engaged with the abutment ring 23, 25 the blades thus being held in the outstanding positions shown in solid line in Fig. 1. At this point it may profitably be observed that when the occasion for the use of the structure has passed the nut 28 may be 30 backed off the fingers 27, the blades 26 being folded into the dotted line positions of Fig. 1, the blades then lying in approximate parallelism with the support 1. The nut 28 may then be advanced on the stem 35 22 and, as shown at 29, the nut will engage with the fingers 27 of the blades and hold the blades in parallelism to the support 1 as above mentioned.

In practical operation, the fingers of the 40 operator are engaged with the elements 3 and the slide tube 6 is moved in the direction of the arrow A by the pressure of the palm of the hand of the operator against the head 7. During this operation, the 45 spring 9 is put under compression, the same being engaged at one end by the head 7 and at the other end by the abutment ring 8. When the slide tube 6 is advanced in the direction of the arrow A, the threaded shaft 50 10 is carried with it, the shaft moving freely through the abutment ring 8. The first function of the shaft 10 as it is advanced is to advance the primary clutch 14 until the teeth 15 thereof coact with the teeth 19 55 of the secondary clutch 18. Thereafter, the threaded shaft 10 coöperates with the primary clutch, to rotate the same, the shaft moving freely through the secondary clutch 18 and through the tubular stem portion 22 60 of the secondary clutch. When the primary clutch 14 is rotated, the secondary clutch 18 will be rotated, carrying with it the ring 23 and the blades 26 which are held to the ring 23 by the action of the nut 28, the ring 65 23 being bound against the shoulder 30 on

the secondary clutch. When pressure on the slide tube 6 is released, the blades 26 and the secondary clutch 18 will continue to rotate by inertia for a time, the spring 9 reacting to draw the primary clutch 14 70 out of engagement with the secondary clutch 18, the projection 16 coacting with the primary clutch 14 to retract the same under the action of the spring 9, it being noted at this point, that the projection, coacting with the primary clutch 14 when the latter is in engagement with the abutment ring 8, limits the movement of the slide tube 6 in the direction of the arrow B under the action of the spring 9. 80

Having thus described the invention, what is claimed is:—

1. In a device of the class described, a support; a rotatable element journaled on one end of the support; a blade pivoted intermediate its ends to the rotatable element, the inner end of the blade extending transversely of the rotatable element, the blade being foldable toward the other end of the support to lie in approximate parallelism 90 with the support; a tubular member movable longitudinally of the rotatable element, the tubular member bearing on the inner end of the blade to hold the blade in outstanding position, the tubular member being movable to lie between the rotatable element and the inner end of the blade when the blade lies in approximate parallelism with the support, thereby to hold the blade in approximate parallelism with the support; and means assembled with the support for rotating the rotatable element. 95

2. In a device of the class described, a support; a secondary clutch journaled for rotation on the support; a fan carried by the secondary clutch; a primary clutch movable longitudinally of the support to coöperate with the secondary clutch; and a shaft threaded into the primary clutch, the shaft constituting means for moving the primary clutch to engage with the secondary clutch, and constituting means for rotating both clutches. 105

3. In a device of the class described, a support; a secondary clutch journaled on the support; a fan carried by the secondary clutch; a primary clutch movable longitudinally of the support to coöperate with the secondary clutch; a shaft threaded into the primary clutch and movable longitudinally of the support, the shaft constituting means for advancing the primary clutch to engage the secondary clutch and constituting means for rotating both clutches at once; and spring means for retracting the shaft and the primary clutch. 125

4. In a device of the class described, a support; a movable element journaled thereon; a blade pivotally mounted intermediate its ends on the rotatable element; and

a holding device movable longitudinally of the rotatable element, the holding device engaging one end of the blade to hold the same in outstanding relation to the rotatable element, and being movable to engage the said end of the blade to hold the blade in approximate parallelism with the support.

In testimony that I claim the foregoing as my own, I have hereto affixed my signature in the presence of two witnesses.

STEPHEN O. DE ORLOW.
